BLENDING SYSTEM

John F. Meissner, La Grange, Ill., assignor to
Hewitt-Robins Incorporated, a corporation of
New York

Application August 18, 1948, Serial No. 44,962

2 Claims. (Cl. 214—16)

1

This invention relates to the handling of ore, coal and similar material requiring to be made available for use in a substantially uniform, blended condition representing an average of the varying assays of incoming supplies of the material. As disclosed in Patents Nos. 858,008 and 2,171,528, for example, a general method or system appropriate for the purpose involves the laying out of the incoming material in a multitude of successive, superimposed layers to build up a large pile, and, then, the removal of the material progressively from the end of the pile in successive "slices" or cuts, more or less parallel to the end face of the pile, every such slice or cut necessarily comprising an average or blend of a short, horizontal length of all of the layers.

The initial laying out or layering of the material is conveniently effected by means of a so-called belt tripper, and the subsequent removal of the material from the pile by a so-called reclaimer.

As heretofore arranged and manipulated, such systems have been set up and operated in the open; and, by reason of the enormous sizes of the piles required (as, for example, of the coal needed to supply a steel mill) have covered large areas. Also, the common practice has been to withdraw the reclaimed material laterally from the foot of the end face of the pile and discharge it to a hopper car operating in a sunken trough or open-topped tunnel running alongside the pile throughout its length, thus adding further to the width of the space required for the system.

The present invention contemplates a system serving the general purposes of the arrangements above referred to, but achieving the results in a manner enabling the capacity of the unit area of the system to be vastly increased; so much so, that without prohibitive expense, the entire pile and reclaiming mechanism may be housed in an enclosure and operated free of interference from the elements. Heretofore, difficulties have been encountered as the result of rain saturation of the piles and also, in northern latitudes, from freezing, both of which conditions can be obviated by the present invention.

In the preferred form herein described for purposes of illustration, the invention incorporates sundry more specific improvements and advantages, as will appear.

In the accompanying drawings:

Fig. 1 is a broken out, longitudinal, partially sectioned view of an enclosure, with a reclaimer and associated mechanism embodying one form of the invention;

2

Fig. 2 is a transverse section of the enclosure of Fig. 1;

Fig. 3 is an enlarged sectional view approximately on the line III—III of Fig. 1;

Fig. 4 is an enlarged portion of the reclaimer and associated mechanism;

Figs. 5 and 6 are further enlarged views of parts of the mechanism shown in Fig. 4;

Fig. 7 is a plan view of the mechanism illustrated in Fig. 5 (with background omitted);

Figs. 8 and 9 are sectional views on the lines VIII—VIII and IX—IX, respectively, of Fig. 6; and

Fig. 10 is a simplified wiring diagram illustrating of certain of the mechanism controls.

Fig. 11 is an enlarged, broken out view illustrating an alternate form of mechanism for progressively opening the slot closure; and

Figs. 12 is a simplified wiring diagram for such alternate form.

Referring generally to Figs. 1, 2 and 3 and particularly to Figs. 1 and 2, there is shown a form of enclosure which includes not only side walls, with their attendant advantages as presently brought out, but also a roof structure, which is the preferred arrangement. This enclosure comprises a rear wall 1, and side walls 2 and 3 which support a suitable roof 4. The rear wall 1 (see Fig. 1) has a built up, inclined face 5 which acts as a backing for the pile 6 of material to be reclaimed, the slope of wall 5 approximating the angle of repose of the material and hence making it convenient to reclaim the pile virtually in its entirety, as will be understood. The enclosure further includes a floor 8 which is made of any suitable material, such as reinforced concrete, capable of withstanding the loads imposed by the pile of material 6 and the reclaiming mechanism.

Located approximately midway between the side walls 2 and 3, is a longitudinal floor opening 10 designated generally by the reference character 10. This opening runs from the front of the enclosure to the inclined face 5 of the rear wall and it may be made in any suitable manner to admit material from the pile 6 to a tunnel 11

which runs from front to rear of the enclosure as shown in Fig. 1. At the rear of the enclosure, the tunnel terminates in a series of access steps 7. The tunnel opening is normally closed against admission of material as the pile is being built up, this closure being effected by means capable of being progressively opened to admit material to the slot, or tunnel opening, only adjacent the foot of the pile. In the present instance such

means is shown as consisting of a series of cross

members, such as angle irons 12 (see Figs. 1, 3 and 4) which are placed side by side and which extend across the opening 10. The arrangement may be as shown in Figs. 3 and 9, in which the irons 12 are supported by suitable projections such as the brackets 13. In any event, the irons 12 can be moved longitudinally of the opening 10 so as to admit material from the pile 6 at any desired position along the opening as will be later described in detail.

As is seen in Figs. 1 and 2, the roof 4 incorporates a structure 15 which runs from front to rear of the enclosure and houses a belt tripper designated generally by the reference character 17. This belt tripper, which may be of any appropriate construction, acts in the known manner to spread incoming material over the length of the floor 8 and thus build up the plurality of layers of which the pile 6 is composed. Preferably, the belt tripper is of the known type adapted to effect a sealing of the enclosure. By using side walls to confine the pile, in conjunction with a floor tunnel between the walls, it will be recognized that a pile of large capacity can be built up on a relatively limited floor area, as contrasted with the space required for the usual unconfined pile with its conveyor tunnel located at one side of the pile.

Referring, in general, to Figs. 1, 3 and 4, and in particular to Figs. 1 and 3, a reclaimer is provided, which includes a main framework or carriage 20 mounted upon wheels 21 which wheels run upon rails 22. The reclaimer is provided with suitable prime movers, such as electric motors, for propelling the reclaimer in either direction along the rails 22. The reclaimer is also provided with a harrow 24 and with suitable means for oscillating it to remove "slices" from the face of the pile 6. Since this much of the reclaimer is well known in the art, it will not be further described.

As the harrow mechanism brings down the material to the foot of the pile 6, it is there caught by a pair of constantly rotating screws 26 and 27, of opposing helices, carried on and suitably driven from the reclaimer. These screws feed the material from across the entire width of the foot of the pile toward the center of the enclosure and, in particular, to the tunnel opening 10. At this point, the angle irons 12 are separated so that the mix can fall through into a hopper car 30, which, in the usual or any suitable manner, is moved in synchronism with the reclaimer 20 so as always to be in position to receive the material fed to it by the reclaimer. As the material enters the hopper car, it is guided therethrough onto a suitable conveyor 31 whence it is carried to any desired terminus, as is well known. Except as below indicated, the details of the hopper car and its drive form no part of the present invention and require no description.

In order to keep the tunnel open at a point near the front of the reclaimer, regardless of the speed at which the reclaimer is advanced into the pile 6, means are provided for progressively moving the slot closure or angle irons 12 toward the front of the enclosure.

In general, such means will be understood to be timed to synchronize with the other related factors of reclaimer movement, hopper car movement and preceding pile face. In the preferred form now to be described, the means for progressively uncovering the tunnel is so synchronized by coupling it directly with the reclaimer.

Referring to Figs. 4 to 9, inclusive, and to Figs.

5, 6 and 7 in particular, two hook members 40 are pivotally mounted on pins 43 carried on the free ends of yoke arms 41 secured to a beam member 45. The latter, which is of T-shaped cross section (see Figs. 8 and 9) is mounted on the reclaimer for fore and aft movement relatively thereto, being suitably guided, as by roller 46. Secured to the underside of member 45, are two spaced rack bars 47 and 48 the downwardly projecting teeth of which are in constant mesh with pinions 49 and 50, respectively (see Fig. 8). These pinions are mounted on and driven by a shaft 52 but through a lost-motion connection. As shown in Fig. 5, a key 51, carried by the shaft, is located in slot 51' in the pinion, so that as the shaft is rotated counter-clockwise from the position indicated, the shaft makes about a quarter turn before picking up and driving the pinion therewith. A similar quarter turn-lag occurs when the shaft is subsequently rotated in the reverse direction. Mounted for sliding movement relative to the rack bars 47 and 48 is a third rack bar 55 (see Figs. 7, 8 and 9) which is in constant mesh with a pinion 56, secured directly to shaft 57. Shafts 52 and 57 are journaled in the main framework of the reclaimer. Mounted upon shafts 52 and 57 are sprocket wheels 59 and 60 which are driven by chain 61 by means of a reversible electric motor carried on the reclaimer. As seen in Figs. 5 and 7, the left-hand end of rack bar 55 has fastened thereto, yoke arms 65 similar to the arms 40 and at their free ends carrying pins 67. These pins extend through slots 68 in hook members 40 (see Fig. 5) and are rigidly secured in the arms 65 and 66. Thus it is seen that if rack bar 55 moves relative to rack bars 47 and 48, the hooks 40 will be caused to rotate about their pivots 43 in a direction dependent upon the direction of motion of bar 55, thus raising or lowering the hooks.

As indicated in Figs. 5 and 6, each angle iron 12 may be formed with dimples or depressions 70 to receive the hooks. The irons 12 also have, secured to each end thereof, small plates 72 upon which plates (see Fig. 9) they slide and which, by holding the trailing edge of each iron 12 slightly raised, serve to insure an overlapping of the irons and an effective sealing of the tunnel slot or opening.

Before referring in detail to the control mechanism by which the rack bars are manipulated, reference will be made to the general operation of the reclaimer and its associated elements. Assuming that the pile 6 has been built up to substantially fill the enclosure and is ready for reclaiming, a group of angle irons 12 is first removed from the series adjacent the foot of the pile of material, as indicated in Fig. 5. In this instance, four of the angle irons have been removed, and to the extent of the width of these four angle irons, the entrance to the tunnel 11 is opened. The reclaimer is now advanced to the face of the pile and the harrow and the reclaimer screws are set in motion to bring down the material and feed it toward and through the now exposed tunnel opening. By means of the control mechanism below described, the rack bars are periodically and automatically manipulated in such manner as to cause the hook members 40 to reach forward, ahead of the reclaimer, grab the angle irons on the far side of the tunnel opening, and draw such angle iron back across the opening into contact with the last angle iron on the near side. This operation is repeated from time to time with the result that the tunnel opening represented by

the gap in the series of angle irons, is caused to advance in step with the advance of the reclaimer throughout the entire length of the pile of material. When the whole pile has thus been reclaimed, the four removed angle irons can be inserted at the far end of the tunnel, that is, adjacent the foot of the sloping end wall; then, after the next pile has been built up, four angle irons are again removed at the foot of the exposed face of the pile, as above described.

The control mechanism by which the foregoing manipulation of the rack bars is accomplished includes a control lever 75 pivotally mounted at 76 on the body of the reclaimer and so located that, as the harrow first attacks the pile of material, the lower end 77 of lever 75 rests on the top of the last angle iron ahead of the opening caused by the removal of the group of four angle irons, as above described. As the reclaimer moves bodily forward, lever 75 moves over the top of the angle iron on which it rests until it falls by gravity into the dotted line position indicated in Fig. 6. This lowering of the front end of lever 75 raises its rear end or tail portion 79, and the latter elevates a switch plunger 78 and energizes a motor control circuit, as illustrated in the Fig. 10 wiring diagram.

Referring now to Fig. 10, the upward movement of plunger 78 causes contact 82 to bridge contacts 81, thereby completing a circuit which may be traced as follows: From input lead 83 through contacts 81, lead 84, through switch arm 85 of a reversing switch R, lead 86, through field winding 87, leads 88 and 89, through switch arm 90 of the reversing switch, lead 91 and through rotor winding 92 to the main lead 93. The motor 87-92 is thus energized and, through chain 61 (Fig. 4) drive shafts 52 and 57 counterclockwise. Referring to Fig. 5, rotation of shaft 57 causes immediate movement of lower rack bar 55, to the left, the upper rack bars remaining stationary due to the lost-motion connection 51-54. Such movement of rack bar 55 swings the hook members 40 clockwise about their pivots 43. After the hook members have thus been raised, the lost motion between shaft 52 and pinion 49 is taken up so that all three rack bars 41, 48 (Fig. 9) and 55 (Figs. 8 and 5) then move to the left, as a unit, to the dotted line position of Fig. 5.

On some part of the rack mechanism, means are provided for reversing switch R to lower the hook members, retract the rack members and bring the motor 87-92 to rest, such means being indicated in Figs. 5 and 10, as comprising three ears 100, 101 and 102. After the motor 87-92 has been energized and the member 45 has just started to move to the left, ear 102 moves away from the depending arm 105 (Fig. 10) of a bell crank 106, permitting the latter to swing clockwise under the influence of a spring 107, thus raising plunger 108 and causing contact 109 to bridge contacts 110 of a holding switch H arranged in parallel with switch 81-82. When member 45 and the racks reach the dotted line position of Fig. 5, the ear 101, by engagement with actuator bar 112 (Fig. 10) throws the reversing switch arms 85 and 90 to the positions shown in dotted lines, thereby reversing the current in the motor field and the direction of rotation of the motor. Rack 55 immediately starts back toward the reclaimer and, in so doing, swings hook members 40 counterclockwise about their pivot pins 43 into engagement with the depressions 79 of the angle iron 12 at the foot of the material pile 6. By this time the lost motion

between shaft 52 and its pinion 49 has again been taken up and all racks then move to the right as a unit, hook members 40 carrying the engaged angle iron 12 with them. In due course the angle iron being traversed passes beneath, engages and raises control lever 75, thereby breaking the motor circuit through contacts 81 and 82 (Fig. 10). However, the motor circuit is maintained by holding switch H, permitting the motor to retract the rack bars to fully restore lever 75 to its full line position. As this position is reached, ear 100 acts upon arm 112 to restore the reversing switch to its original position and ear 102 coincidentally acts upon arm 105 to break the motor circuit at the holding switch H.

As stated above, this sequence is repeated from time to time until the entire pile has been reclaimed; and, as will now be apparent, the control of the floor opening is not only wholly automatic in the sense that it requires no attention from the operator, but also in that the rate at which the slot opening is progressively advanced varies directly with the speed at which the operator advances the reclaimer.

In the alternative arrangement diagrammatically illustrated in Fig. 11, the mechanism by which the floor opening is progressively advanced is carried by the hopper car in the tunnel, rather than by the reclaimer. Only so much of the hopper car 30 is shown as is necessary to indicate the additions to the hopper car 30 of the first described arrangement.

Mounted on the hopper car are front and rear sprocket shafts 115, 116 carrying sprockets 117, 118, respectively, connected by chain 119 of which one of the links carries a lug 120. Sprocket shaft 116 is driven by chain 121 from a motor-driven shaft 122. In the wiring diagram, Fig. 12, shaft 122 is indicated as driven directly by motor 123.

In this form, each angle iron 12' is provided with a depending lug 124 for engagement by chain lug 120, whereby the angle irons are successively moved from front to rear of the floor opening for the purpose above described. The hopper car is advanced in synchronism with the reclaimer, and the general arrangement is such that, periodically, the motor 123 is energized to effect one turn of shaft 122 and one complete circuit of the chain lug 120, in the course of which it picks up one of the angle irons at the left of the tunnel opening (as viewed in Fig. 11), and moves it to the right of the opening. While only one chain 119 is shown in the diagram, it will be understood that in order to keep clear of the material passing down through the tunnel opening, two such chains and pairs of sprockets are mounted on the car, one at each side of the tunnel opening.

The starting of the motor for each cycle is controlled by a switch 125 mounted on the hopper car and actuated in one direction by a spring 126 and in the other direction by a lever 127 positioned for engagement by lugs 124. In the arrangement illustrated, lever 127 is depressed by a lug 124 (as the hopper car advances) to open switch 125 and, as the free end of lever 127 moves out from under lug 124 (as the hopper car continues to advance) the switch is closed by spring 126. The stopping of motor 123 is effected by a switch 128 which is opened by a cam actuator 129 mounted on shaft 122 and is closed by a spring 130 (Fig. 12). Thus, in the full line position of the parts shown in Fig. 11, motor shaft 122 is at rest (switches 128 and 125

both being open). As the hopper car continues its slow movement to the left, sprockets 117, 118 advance to positions 117', 118' and lug 120 to position 120', lever 127 moves out from under that lug 124 which is shown holding it depressed and spring 126 then closes switch 125 to start motor 123 and effect one cycle of movement of shaft 129, chain 119 and lug 120, as above stated, thereby moving one of the angle irons across the tunnel opening.

Referring to the wiring diagram, Fig. 12, it will be noted that a time delay switch 131 is provided. While it may be of any preferred type, it is indicated as controlled (opened) by a heater coil 132 which is energized as the result of the closure of switch 125 and, through switch 131, the motor circuit (which is at this time open at switch 128) is completed. As the motor starts, member 129 permits spring 130 to close switch 128, which is in parallel with switch 131. Before the shaft has completed its turn, switch 131 will have been opened by heater coil 132, switch 125 will have been re-opened by engagement of the next succeeding lug 124 with lever 127, thereby breaking the circuit of heater coil 132, and switch 131 will have re-closed. Accordingly, when shaft 122 completes its turn, and member 129 again opens switch 128 to stop the motor, the several switches will again occupy the positions shown in Fig. 12 in readiness for the next cycle, which starts as lever 127 again moves out from under lug 124 in response to the advance of the hopper car.

It will be apparent that the enclosure can be provided with suitable doors at its open end (toward the right as viewed in Fig. 1) and rendered substantially dust-tight. Also, to the end of minimizing the hazard which would result from the existence of an explosive atmosphere within the enclosure, the free space within the latter may be maintained under slight negative pressure.

As will now be apparent, the principles of the invention are susceptible of embodiment in various forms to suit the exigencies of any particular installation, and hence the details described are to be understood to be illustrative only.

In the premises, the following is claimed:

1. In a system of the character described, the combination of a receiving floor for a pile of layered material, a tunnel beneath the level of the floor having an entrance slot in the floor extending longitudinally thereof intermediate the lateral boundaries of the pile of layered material

thereon, means normally closing the said slot to prevent the gravity flow of material through the slot into the tunnel, a hopper car adapted to operate within the tunnel, a reclaimer adapted to be advanced into the pile along a path paralleling the tunnel and its entrance slot and including means for directing the reclaimed material toward the slot, and means carried by the hopper car for progressively opening the slot closing means to admit reclaimed material to the hopper car.

- 5 2. In a system of the character described, the combination of an enclosure including an elongated receiving floor bordered by walls along two sides and across one end, a supporting structure mounted on the side walls and extending over the said floor, layering mechanism carried by said supporting structure between the side walls and extending throughout the length of the floor, 15 said enclosure adapted to receive a pile of layered material delivered by said mechanism and confined throughout a substantial portion of its height by said end and side walls and with the pile terminating at the end opposite to the end 20 wall in an exposed face slope determined by the angle of repose of the material, a tunnel beneath the level of the floor having an entrance slot in the floor, said tunnel and entrance slot extending longitudinally of the enclosure intermediate 25 the side walls, means normally closing the slot to prevent the gravity flow of material through the slot into the tunnel, a hopper car adapted to operate within the tunnel and actuating mechanism for opening the slot closing means, said 30 actuating mechanism being mounted on the hopper car for movement therewith.

JOHN F. MEISSNER.
